STIRRING UTENSIL

Ernest Thomas, Roselle, Ill., assignor to Ekco Products Company, Chicago, Ill., a corporation of Delaware

Filed June 15, 1962, Ser. No. 70,558

Term of patent 14 years

(Cl. D44—1)

Fig. 1

Fig. 2

Fig. 3

Fig. 4

FIG. 1 is a side view of a stirring utensil showing my new design.

FIG. 2 is a reverse side view thereof.

FIG. 3 is a section taken along line 3—3 of FIG. 1.

FIG. 4 is an enlarged section taken along line 4—4 of FIG. 2.

I claim:

The ornamental design for a stirring utensil, substantially as shown.
